PROTECTIVE SHEATH FOR COWS' TEATS

Frederick Edward Brown and Peter Martin,
Hyde, EnglandApplication July 28, 1949, Serial No. 107,188
In Great Britain August 3, 1948

8 Claims. (Cl. 128—132)

1

In spite of advances in veterinary science, large numbers of valuable cows are slaughtered every year as a result of disease of their milking organs. Many of the worst diseases arise from germs or poison, mainly fly-borne, passing up through the teats to the udder.

The applicants have discovered that the toll exacted by such diseases can be very materially reduced by protecting the teats at appropriate times by means of sheathes which cover the milk outlets.

To be successful in use and to be acceptable to the farmer, such sheaths must not damage the teats which are delicate organs or cause the cow discomfort; must be capable of being easily placed in position and stripped off and yet remain securely in position in spite of the flabbiness of the teats and the conditions under which a cow lives; must be cheap to manufacture.

The general aim of the invention is to provide a sheath having such qualities.

The preferred form of protective sheath in accordance with the invention is made of a flexible elastic material such as rubber and has a bulbous body portion closed at one end and merging into a neck at the other. The inside of the neck is coated with a plurality of adhesive patches which extend over the greater part of the circumference of the neck and which are covered by strips which adhere lightly to the passage and extend beyond the open end of the neck.

Such a sheath has the desirable qualities enumerated above as will be clear from the following description of the accompanying drawings in which:

Figures 1 and 2 show the preferred form of sheath in position on a teat at different stages in its being fitted in position thereon.

Figure 3 is an elevation, partly in section, showing on a larger scale the upper end of the sheath shown in Figures 1 and 2 and illustrating the manner in which it is used.

Figure 4 shows in elevation a manner of stiffening the neck of the sheath shown in Figures 1 and 2.

Figure 5 is a section taken on the line V—V in Figure 4.

Figure 6 is a section corresponding to Figure 5 of an alternative manner of stiffening the neck and

Figure 7 is a perspective view of a sheath having a neck of polygonal section.

The sheath shown in Figures 1-3 has a bulbous portion A and a neck B. These two portions are joined by a connecting portion C which ta-

2

pers at about 45° to the longitudinal axis of the sheath and provides a smooth transition from one to the other, which is desirable in order that the sheath may be easy to mount and may not damage the teat.

The shape and nature of a cow's teats are such that there is a tendency for the open end of the neck of the sheath to be opened and to roll over with the consequence that the sheath slides off. This tendency is counteracted by the provision of an external bead D at the open end of the neck.

Many experiments made by the applicants have led to the empirical establishment of the following dimensions which lead to the production of a sheath which is easy to mount, which remains in position for a reasonable length of time and does not lead to irritation or damage of the teat:

Length of neck, about $\frac{1}{4}$ — $\frac{3}{8}$ inch.

Bead, not more than $\frac{1}{16}$ inch thick.

Thickness of neck, not more than 0.02 inch.

In general, the thickness of the bulbous portion should not be greater than 0.02 inch, but this dimension is not so vital as the others.

The neck is coated internally with three patches of adhesive E which are separated by gaps F of less width than their own width so that the neck is coated over the greater part of its circumference. The patches are covered by strips G which proceed from the open end of the neck down to the lower edge of the adhesive patch and up again. They are long enough to project out of the neck as shown in Fig. 3. They are preferably lightly tacked to the neck E so as to retain the position shown on the left hand side of Fig. 3.

When the sheath is to be used, its neck is expanded and is passed over the teat J into the position shown in Fig. 1. When it is in position, the strips G are pulled upwards and are thus stripped off the adhesive patches as indicated in Fig. 3. The sheath is thus caused to adhere to the teat as shown in Fig. 2 and the presence of the adhesive does not, in any way, impede the placing in position of the sheath.

It is advantageous for the neck to have that amount of rigidity which will resist its being rolled down. It can, with this object in view, be provided with crimps K as shown in Figs. 4 and 5. Such crimps are easily provided in a sheath made by a dipping process; in the case of a moulded sheath, the crimps are best replaced by light solid ribs K' as shown in Fig. 6.

The adhesive should be one which retains its adhesive powers over a wide range of temperature and must, of course, be hygienic and medi-

cally acceptable. Zinc oxide as used in adhesive bandages is very suitable.

The protective strips must be of a material to which the adhesive will adhere less well than it does to rubber so that when they are pulled away, they will be stripped from the adhesive. They should also be thin, smooth and flexible and preferably substantially inelastic. Good results have been obtained with strips of a plastic of the polyvinyl chloride kind. Thin, strong woven strips having a glazed surface can also be used. Draughtman's tracing cloth is a suitable material of this kind.

It is of advantage to provide ventilation holes as shown at L in Figs. 1, 2 and 7. Their main purpose is to allow for the escape of air during the fitting of the sheath and also during use when, for example, the air trapped in the sheath may be subjected to pressure because the cow is lying on a teat or because a teat of a lying cow is trodden on. The ventilation holes must be small—preferably not greater than $\frac{1}{16}$ in. diameter. They are best provided immediately below the neck.

Sheaths for general use are preferably made, by a dipping process, from surgical rubber latex. Synthetic latex can, however, also be used; indeed, some forms of synthetic rubber have certain advantages over natural rubber. Thus, if a teat be damaged, it is usual to anoint it with healing oil. Such oil causes rubber to deteriorate and lose its stretch, but has no such effect on synthetic rubbers of the butyl kind which are oil-resistant. The sheaths can, however, also be made by moulding.

A maximum thickness of bead of $\frac{1}{16}$ in. at the open end of the neck has been indicated. The actual thickness which is adopted depends upon the diameter of the neck. The tightness of the bead depends upon both these factors and, therefore, the smaller the diameter of the neck, the smaller will, in general, be the thickness of the bead. With the smaller sizes of sheath, a bead thickness of about 0.03 to 0.04 in. gives very satisfactory results.

As the solvent in some adhesives is liable to be absorbed by rubber and lose its adhesive power, it can be advantageous to provide the patches in the form of very thin strips of oil resisting material coated on both sides with the adhesive. Such a double covered strip can be made to adhere strongly to rubber and to remain adherent thereto. The exposed layer of adhesive, i. e. on the side of the strip remote from the rubber, would then be covered by a protective strip as explained above. The adhesive which is to be brought into contact with the teat is thus sandwiched between two non-absorbent materials which will enable the sheaths to be kept in stock for long periods without fear of deterioration of the adhesive.

The necks of the sheaths shown in Figs. 1-6 are cylindrical. It will be appreciated that the application of the adhesive and the cover strips may, and generally will, distort the necks so that they do not appear to be cylindrical until they are placed in position on the teats. The term "cylindrical" is to be construed accordingly.

In a modified form of the invention shown in Fig. 7, the neck B' is made polygonal in cross section—for example, hexagonal or octagonal. This can be particularly advantageous when the sheaths are made by dipping as the arrises will form stiffening ribs of the kind referred to above.

We claim:

1. A protective sheath of flexible elastic ma-

terial closed at one end and open at the other and comprising a bulbous body portion extending from said closed end, a neck portion extending from said open end, an adhesive coated on the inside of said neck portion in the form of a plurality of patches extending over the greater part of the circumference of said neck portion, and a plurality of strips each lightly stuck to and covering a different one of said patches and disposed axially of said neck and having a free end beyond that end of the associated patch which is remote from the open end of the sheath.

2. A protective sheath of flexible elastic material closed at one end and open at the other, comprising a body portion extending from said closed end, a neck portion extending from said open end and of a length which is small in comparison with that of said body portion, an adhesive coated on the inside of said neck portion in the form of a plurality of spaced apart patches extending from said open end, and strips of substantially inextensible material covering said patches from the edge thereof nearest to said open end to and beyond the edge remote from said open end thereby to provide free ends which can be pulled from outside the sheath to uncover said patches.

3. A protective sheath of flexible elastic material closed at one end and open at the other, comprising a body portion extending from said closed end, a neck portion extending from said open end, an adhesive coated on the inside of said neck in the form of a plurality of spaced apart patches extending away from said open end and over the greater part of the circumference of said neck, and a plurality of strips of substantially inextensible material covering said patches and extending from said open end into said neck and back again beyond said open end, each of said strips being lightly tacked to itself in the vicinity of said open end.

4. A protective sheath of flexible elastic material closed at one end and open at the other, comprising a body portion at said closed end, a neck portion at said open end of a length which is small in comparison with that of said body portion, an external bead at said open end, a connecting portion between said body portion and said neck portion free from any local constriction, an adhesive coated on the inside of the sheath in the form of a plurality of patches extending from said open end at least over the whole length of said neck portion and over the greater part of the circumference thereof and a plurality of strips of smooth flexible substantially inextensible material each covering one of said patches and extending beyond the edge thereof remote from said open end by an amount greater than the length of patch which is covered.

5. A protective sheath of flexible elastic material closed at one end and open at the other and comprising a bulbous body portion extending from said closed end, a substantially cylindrical neck portion extending from said open end and a connecting portion between said body and neck portions providing a smooth transition with no local thickening of the wall of the sheath, said neck portion being provided with a plurality of external ribs extending from said open end to said connection portion, an adhesive coated on the inside of said neck portion in the form of a plurality of patches extending over the greater part of the circumference of said neck portion, and a plurality of strips each lightly stuck to and covering a different one of said patches, and

disposed axially of said neck and having a free end beyond that end of the associated patch which is remote from the open end of the sheath.

6. A protective sheath as claimed in claim 5, in which said ribs are in the form of crimps.

7. A protective sheath as claimed in claim 6, in which said ribs are solid.

8. A protective sheath as claimed in claim 1 in which said neck is of polygonal cross-section in the unstressed condition.
